UNITED STATES PATENT OFFICE

171,540

DECANTER OR SIMILAR ARTICLE

Otto Grun, New York, N. Y.

Application July 10, 1953, Serial No. 25,884

Term of patent 14 years

(Cl. D58—9)

To all whom it may concern:

Be it known that I, Otto Grun, have invented a new, original, and ornamental Design for a Decanter or Similar Article, of which the following is a specification, reference being had to the accompanying drawings forming a part hereof.

Fig. 1 is a front elevational view of a decanter or similar article, showing my new design;

Fig. 2 is a side elevational view thereof taken from the right side of Fig. 1; and

Fig. 3 is a rear elevational view thereof.

I claim:

The ornamental design for a decanter or similar article, as shown.

OTTO GRUN.
